United States Patent Office

Des. 205,372
Patented July 26, 1966

205,372

LAMP

David K. Walz, Doraville, Ga., assignor to Lithonia
Lighting Products Company, Conyers, Ga., a corporation of Georgia

Filed June 14, 1965, Ser. No. 85,726

Term of patent 14 years

(Cl. D48—20)

FIG.1

FIG.4

FIG. 1 is a perspective view of the lamp;
FIG. 2 is a side elevational view of the lamp in horizontal position;

FIG. 3 is a top plan view of the lamp in horizontal position;

FIG. 4 is a front elevation of the lamp; and

FIG. 5 is a side elevation of the lamp in vertical position.

The dominant features of my design reside in the portions shown in full lines.

I claim:

The ornamental design for a lamp, substantially as shown and described.
